UNITED STATES PATENT OFFICE

HARRY A. LEONARD, OF HOPEDALE, MASSACHUSETTS, ASSIGNOR TO DRAPER CORPORATION, OF HOPEDALE, MASSACHUSETTS, A CORPORATION OF MAINE

WARPER TREADLE

Application filed June 24, 1931. Serial No. 546,476.

This invention relates to the starting treadle mechanism of a beam warper.

The beam warper of the type to which this invention relates is provided with automatic mechanism for stopping the warper upon the happening of various occurrences such as the breaking of a warp or the completion of the winding of a predetermined length of warp. The mechanism for starting the warper comprises the starting treadle having a treadle board extending transversely of the warper at the front near the floor so that the operator may start the warper at any position at the front of the loom by stepping on the treadle board and depressing the treadle. The high speed warpers which have come into use handle beams of large diameter and great difficulty has been experienced in providing a starting treadle which will always be readily accessible for operation by the foot of the operator even when the beam is full and which at the same time will not interfere with the doffing of the beam.

The present invention has for its object to provide a starting treadle mechanism in which the treadle board supporting arms are extensible and contractible and so arranged that the treadle board is always in position readily accessible to the foot of the operator and at the same time, when contracted, position the treadle board so that there will be no interference with the beam as it is being doffed or removed from and replaced in the warper.

These and other objects and features of the invention will appear more fully from the accompanying description and drawings and will be particularly pointed out in the claims.

A type of high speed beam warper in which a preferred form of the present invention is embodied is disclosed in the patent to Trevett and Davis, No. 1,794,345, granted February 24, 1931, and in view of the disclosure of this patent, it is only necessary here to illustrate and describe those features of a beam warper with which the present invention is particularly concerned, together with a preferred form of the invention.

In the drawings:

Fig. 1 is a side elevation partially broken

away of the warper with some of the parts omitted.

Fig. 2 is a detail in vertical cross section showing the starting treadle contracted and in dotted lines extended.

Fig. 3 is a detail in plan and partially in horizontal cross section showing a portion of the treadle mechanism contracted and in dotted lines extended.

The beam warper shown comprises side frames 1 and 2. Beam supporting arms, the left-hand one of which 3 is shown, are pivoted at 4 in the end frames. These arms support gudgeon blocks 5 which slide on the arcuate tracks 6 of the forwardly projecting portions of the arms 3. In these gudgeon blocks are journaled the trunnions 7 of the warp beam having the cylindrical barrel 8 and the disk-like heads 9 and 10. The warp beam is driven by the frictional engagement of a rotated drum 11 engaging the sheet of warp 12 as it is wound on the barrel 8. Consequently as the mass of warp increases, the beam gudgeons 5 are forced upwardly and forwardly on the tracks 6, the beam heads 7 moving from a position such as shown in full lines to a position such as shown in dotted lines 13.

When the beam is wound full and is to be doffed or removed from the warper, the forward ends of the arms 3 are moved downward to a position such as shown in dotted lines at 14. This is done by swinging the arms on the pivots 4 in the usual manner. This brings the full beam into a position such as indicated in dotted lines at 15.

The starting treadle in which the invention is embodied comprises a pair of similar extensible and contractible arms with the forward ends of the front sections of these arms connected by the treadle board. Since the construction is the same at both sides, it is sufficient to illustrate that at one side. A shaft 16 extends transversely between the side frames 1 and 2 at the bottom near the rear and forms the pivot for the treadle. A mechanism connected to and operated by this shaft, including the arm 17, actuates the starting mechanism of the warper when the shaft 16 is rocked clockwise, as viewed in

Figs. 1 and 2, all in a familiar manner, and as shown, for example, in the above-mentioned patent. Each treadle arm rear section 18 is secured as by a set screw 19 to the pivotal shaft 16 and extends forwardly therefrom. These rear sections are connected at their forward ends by a rod 20 and each is also provided with an inwardly projecting stud 21 extending parallel to the rod 20 and well to the rear thereof. Each rear section is also arched at 22 to avoid interference with the tie rod 23. Each treadle arm front section 24 is longitudinally slotted at 25 substantially throughout its length and this slot fits over the rod 20 and the stud 21. At the forward ends the front sections 24 are connected by the treadle board 26. The treadle arms extend forward from the pivotal shaft 16 beneath the beam and just inside of the beam heads.

The length of the treadle arm sections is such that when the arms are extended, the treadle board, as shown in full lines in Fig. 1, stands well at the front of the beam and in a position where the operator may readily place the foot upon the treadle board and depress the treadle even when the beam is wound full. Thus at all times with the treadle arms extended the treadle board is readily accessible to the foot of the operator. But in this position it would be impossible to doff the beam because when the arms 3 are swung downward and the beam brought into position shown at 15, it would engage and interfere with the treadle. With this invention, when the beam is to be doffed, the treadle arms are contracted and brought into the position shown in dotted lines in Fig. 1 and in full lines in Figs. 2 and 3. The treadle board and the front arm sections are then in a position where there is no interference with the beam during the doffing operation.

Each front arm section is preferably provided with a recess 27, see Fig. 2, at the rear end of the slot 25 adapted to engage beneath the stud 21 when the arm is extended and thus prevent unintentional contraction of the arm and a small leaf spring 28 secured at 29 to the rear end of this arm section cooperates with the recess 27 to insure engagement of the recess 27 and the stud 21. A ledge or inward projection 30 on each rear arm section is also preferably provided to support the rear end of the corresponding front section when the arms are contracted, as shown in Figs. 2 and 3.

The treadle arms are readily extended and contracted. When in the extended operative position shown in Fig. 1, the operator raises the treadle board slightly with the foot to release the recesses 27 from the studs 21 and then shoves the treadle board rearward, contracting the arms and bringing the rear ends of the forward arm sections into engagement with the ledges 30. When the treadle arms are to be extended from the contracted posi-

tion shown in full lines in Figs. 2 and 3, the treadle board is seized by the foot or hand and drawn forward into operative position.

There is thus presented a very simple and effective construction by means of which the starting treadle of the beam warper, when its arms are extended, is always readily accessible to the operator's foot even when the beam is full and in which, when the arms are contracted, there is no danger of interference or damage to the machine during the doffing operation.

Having thus described the invention, what is claimed as new, and desired to be secured by Letters Patent, is:

1. A warper for winding a headed beam comprising beam supporting arms having their forward ends movable downward for doffing the beam, and a starting treadle having a pair of arms pivoted at their rear ends and extending forward beneath the beam and between the heads thereof and a treadle board connecting the forward ends of the arms in which each of said arms is extensible and contractible to enable the operator when the arms are extended and the beam is full readily to operate the treadle and to enable the beam to be doffed without interfering with the treadle when the arms are contracted.

2. A starting treadle for a beam warper comprising two similar extensible and contractible arms pivotally mounted at their rear ends and each composed of two relatively slidible sections and a treadle board connecting the forward ends of the front sections, the said arms when extended permitting ready access of the operator's foot to the treadle board even when the beam is full and when contracted permitting doffing of the beam without interference with the treadle.

3. A starting treadle for a beam warper comprising two similar arms pivotally mounted at their rear ends, each arm composed of a rear section and a front section, a rod connecting the forward ends of the rear sections, a stud projecting from each rear section parallel with the rod, each front section longitudinally slotted to fit over the rod and adjacent stud and slide longitudinally of the rear section, and a treadle board connecting the forward ends of the front sections.

4. A starting treadle for a beam warper having the construction defined in claim 3, in which each of said front sections is provided with a recess at the rear end of its slot to engage the stud and prevent unintentional contraction of the arms when extended.

5. A starting treadle for a beam warper having the construction defined in claim 3, in which each of said front sections is provided with a recess at the rear end of its slot to engage the stud and prevent unintentional contraction of the arms when extended, and a

spring on the said section cooperating with the recess to insure engagement of the recess and stud.

6. A starting treadle for a beam warper comprising the construction defined in claim 3, together with a projection on each rear section to support the rear end of the corresponding front section when the arms are contracted.

10 In testimony whereof, I have signed my name to this specification.

HARRY A. LEONARD.
